STORAGE CRIB

Esther K. Pennington, Oak Park, Ill.

Application October 6, 1945, Serial No. 620,747

1 Claim. (Cl. 189—3)

1

This invention relates to a storage unit and more particularly to a storage crib of the prefabricated portable type which may be readily erected or disassembled and which is adapted to hold corn and other grains and products for storage purposes.

Heretofore, numerous prefabricated, portable storage cribs have been devised and utilized for the storage of corn and other grains and products which were adapted to be assembled by the customer or knocked down for removal to another location. However, because of their portable nature there prior cribs possessed various inherent weaknesses which rendered their use unsatisfactory and their commercial sale relatively unsuccessful. The principal deficiency of these prior cribs was their general tendency to buckle or bow out of shape or to even collapse when under load, i. e., when the crib was filled with a substantially full complement of corn or other products. It was found that the relatively great outward pressure of the contents caused the main supporting posts to bow outwardly or become deformed which thereafter put such undue stress on other parts of the crib including the various bracing and securing means that total collapse sometimes resulted. The means for uniting and securing together the various elements of the framework were found to be of insufficient structural strength under full load.

As a result, numerous attempts have been made to correct the deficiencies of the early portable cribs, but these attempts for one reason or another have been relatively unsuccessful. Some of these attempts comprised the provision of additional bracing or reinforcing means which not only tended to reduce the overall capacity of the crib but also rendered the structure heavier, more expensive and more complicated and, therefore, more difficult to erect or disassemble. It was even found that the additional bracing or reinforcing means failed to accomplish its intended purpose and that the structures under normal operating load still became bowed or deformed in some respect.

Other attempts comprised the use of material of a much heavier stock or thickness which tended to increase the structural strength of the crib and its ability to resist deformity or collapse under full load, but which at the same time resulted in a much heavier construction. Such a heavy construction necessarily raised the manufacturing and shipping costs of the crib and also had the disadvantage of making its assembly or disassembly more difficult.

2

A great many of these prior cribs incorporated wire mesh retaining walls with a structural steel framework and these also proved to have deficiencies or other undesirable characteristics which rendered them impractical. In some such structures the wire mesh was formed in individual panels which were adapted to be secured to the sides of the framework by separate securing means, but these panels under load tended to become bowed outwardly or to be forced away from the framework. It was found that the wire mesh lent no reinforcing strength to the crib as a whole and the full load was still thrust upon the main supporting posts of the framework or upon the bracing and the securing means. In other structures the wire mesh was secured in single lengths around the inside of the framework by a plurality of fastening means, but in these instances also the full load or thrust was still placed upon the main supporting posts with the wire mesh lending little or no supporting effect thereto. The wire mesh also still tended to bow or stretch outwardly under load to a considerable degree between the posts causing an unsightly and out-of-shape structure in which the stresses and strains were exerted directly against the supporting framework in such an abnormal and undesirable manner as to cause in time total collapse of the structure.

30 Another distinct disadvantage of the prior cribs which combined a framework and wire mesh retaining walls was the extreme difficulty and tediousness of the job of securing the mesh to the various upright and horizontal elements of the framework at a multitude of places. Since the wire mesh was merely placed against the inner surfaces of the framework, it was necessary that the fastening means be manually engaged with the mesh and the framework at each and every one of the appropriate places in order to support the mesh in contents retaining position and in order to prevent displacement of the mesh from its proper vertical position and to prevent its pulling away from the framework when under load. This manual operation in securing the mesh was necessarily time-consuming and the securing means were often-times ineffective, with the result that such cribs left much to be desired.

It is, therefore, one of the objects of the present invention to provide an improved storage crib of the prefabricated, portable type that may be readily erected or knocked down, and which is strong, durable and capable of holding a full load of corn and other grains or products without distortion or collapse.

Another object of the present invention is to provide an improved storage crib of the foregoing character comprising a structural framework and a wire mesh which are so constructed and arranged that they are mutually supporting and adapted to resist distortion and collapse under load.

Still another object is to provide an improved storage crib comprising a structural framework and a flexible retaining sheet encompassing and tightly engaging the outer surfaces of said framework under constricting tension, said flexible sheet exerting an inwardly directed pressure and tending to force said framework inwardly so as to assist said framework in successfully resisting the outward pressure of the contents within said crib.

A further object of the invention is to provide an improved storage crib comprising a structural framework and a flexible sheet encompassing and tightly engaging the outer surfaces of said framework, the flexible sheet being of lesser length than the outer peripheral extent of said framework and having its ends spaced apart in its initial unconstricted condition, and means for drawing the ends of said sheet toward each other so as to cause the sheet to tightly engage the outer surfaces of said framework with a constricting tension.

A still further object of the invention is to provide an improved storage crib that is of such construction that distortion or collapse thereof either in an inward or outward direction when under full load, is successfully prevented.

Other and further objects and advantages of the present invention will become apparent as this description progresses, reference being had to the accompanying drawing, in which:

Figure 1 is a front perspective view of a storage crib comprising my invention with portions of the upper and lower lengths of wire mesh broken away;

Fig. 2 is an elevational view of the lower length of wire mesh in extended condition before application to the structural framework of the crib and with the central portion thereof broken away;

Fig. 3 is an elevational view of the upper length of wire mesh also in extended condition before application to the structural framework and also with the central portion thereof broken away;

Fig. 4 is a top plan view of the length of wire mesh shown in Fig. 2;

Fig. 5 is a front elevational view showing the doorway to the crib formed by the end portions of the lower length of wire mesh and the bolt and nut means for drawing the wire mesh tightly about the framework under a constricting tension;

Fig. 6 is a bottom plan view of the structure of Fig. 5, looking in the direction of the arrows; and

Fig. 7 is a top plan view of approximately one-half of the crib, showing in broken lines the position of the wire mesh when under constricting tension but not under full load and its position when under full load in solid lines.

The improved storage crib comprising my invention and illustrated by a preferred embodiment thereof in Figs. 1 to 7 of the accompanying drawings, is of the prefabricated, portable type which may be delivered to a farmer, for instance, in knocked down condition and assembled by him with little assistance and with a minimum of effort for the storage of corn or other products.

The crib may be erected on a prepared foundation of floor (not shown) composed of concrete or wood or may, with efficient and satisfactory results, be supported directly on a level space of ground that is sufficiently high for proper drainage. However, for the purposes of the present invention, the type of foundation is more or less immaterial since the crib functions in substantially the same manner and with the same results on all the various types.

The storage crib shown more particularly in Fig. 1 of the drawings, comprises generally a ten sided structural framework or enclosure about which are tightly drawn under a constricting tension lengths of flexible sheeting, such as wire mesh. The structural framework is comprised of a plurality of main vertical posts, ten in number, which are in the form of angle irons 10 of a strong, light weight steel. These main post irons 10 are each positioned so that one of their respective faces or engles is substantially flush or parallel with the outer periphery of the crib and the other of their respective angles extends inwardly in a substantially radial direction. Secured to the peripheral faces of each of the main post irons 10 at the upper, central and lower portions thereof by means of nut and bolt connections, are three horizontally extending bent tie plates 11, which in turn are bolted at each of their projecting ends to the outer faces of horizontally extending angle irons 12. Thus, between each of the main vertical post irons 10 there are three spaced horizontal irons 12 of strong light weight steel which serve to maintain the posts 10 in proper spaced relationship and in vertical position. These horizontal irons 12 have the further effect of dividing the crib into upper and lower sections and into twenty individual panels as viewed from the exterior.

To further brace the main posts 10 and to maintain them in proper vertical and spaced position, there are provided a plurality of flat diagonal struts or brace irons 13 also of strong light weight steel. These struts 13 are bolted to and extend diagonally between adjacent posts 10 in each panel except the doorway, one end of each strut being bolted to the outer face of one main post 10 and its other end being bolted to the inner face of an adjacent post 10. For more effective bracing and added strength, the bracing struts 13 in the various panels of the crib extend in diagonal directions opposite to the directions of those struts 13 that are in adjacent panels either above or below or to the sides thereof.

As shown particularly in Figs. 1 and 7 of the drawings, the structural framework also includes a plurality of flat tie plates 14 which are bolted to the horizontal faces of the adjacent ends of the upper horizontal angle irons 12 at the top of the structure. These flat tie plates 14, therefore, extend across each one of the ten corners over each of the main vertical posts 10 and serve to maintain the horizontal angle irons 12 and the sides of the structure in the proper angular relationship by preventing hinging movement of those parts, either inwardly or outwardly, about the main posts 10. In an identical manner and for the same purposes, a plurality of flat tie plates 15 of identical construction to the tie plates 14, are bolted to the bottom horizontal faces of the adjacent ends of the lower horizontal angle irons 12 at the bottom of the structure.

After the above numbered structural elements 10 to 14, inclusive, have been assembled in the relationship above described, the two lengths of

wire mesh may be placed one above the other and drawn tightly around the outside of the framework so as to form retaining walls for holding the contents within the crib. The sheet of wire mesh 16 which encompasses the exterior of the lower half section of the crib is shown in extended position before assembly in Figs. 2 and 4 of the drawings, and the wire mesh sheet 17 which encompasses the upper half section of the crib is shown in Fig. 3. The mesh sheets 16 and 17 are provided at each of their extreme ends with a pair of reinforcing elongated angle irons 16a and 16b and 17a and 17b respectively. These end irons 16a and 16b and 17a and 17b, as shown in Figs. 1 and 4, are bolted together by a plurality of bolts 19 and 20, respectively, into the form of a T with the respective ends of the lengths of wire mesh being clamped between the substantially parallel faces of the adjacent end irons by the bolts 19 and 20 respectively.

The wire mesh sheets 16 and 17 are each of lesser length than the outer peripheral extent of the structural framework so that when the sheets 16 and 17 are initially placed about the framework and before they are drawn tightly therearound, their respective ends are spaced apart a considerable distance. As shown clearly in Figs. 1 to 4, inclusive, the wire mesh sheet 16 which encompasses the lower section of the crib is of lesser length than the wire mesh sheet 17 for the upper section, in order that the ends 16a and 16b of the sheet 16 will be spaced farther apart to provide sufficient space for a doorway 21 permitting access to the interior of the crib.

In mounting the lower mesh sheet 16 around the exterior of the lower section of the structural framework, the sheet 16 may be opened up from the rolled condition in which it may be shipped and loosely placed in encompassing relation about the lower portion of the crib. In such loosely assembled position the reinforcing angle irons 16a and 16b on the respective ends of the mesh sheet 16 are spaced a considerable distance from each other with the upper portion of the T formed by these irons extending in a substantially radial direction at right angles to the plane of the mesh sheet 16. As shown in Figs. 1, 5 and 6, in order to draw the mesh sheet 16 tightly about the lower exterior of the crib under a constricting tension, there are provided four elongated rods or bolts 22 having threaded ends and which extend between and through the radially directed portions of the end irons 16a and 16b, two of these rods 22 extending between the lower ends of the end irons and two rods 22 extending between the upper ends thereof. A plurality of nuts 23 are applied to the threaded ends of the rods 22 so as to engage the end irons 16a and 16b and further rotation of these nuts 23 on the rods 22 will draw the ends 16a and 16b of the wire mesh 16 closer together until the wire mesh 16 is stretched or drawn tightly about the exterior of the framework so as to exert a constricting tension or an inwardly directed pressure thereagainst.

In substantially the same manner and by similar means comprising threaded rods 24 and bolts 25, the upper section of wire mesh 17 may be drawn tightly about the exterior of the upper half of the framework so as to also exert an inwardly directed pressure thereagainst. The rods 24 are shorter than the rods 22 of the lower mesh section and extend between and through the radially directed portions of the end irons 17a and 17b of the upper mesh sheet 17 at their

upper and lower ends and at their central portions.

In order to further provide for a somewhat more equalized application of the constricting forces against the outer surfaces of the structural framework, the ends of one of the wire mesh sheets may be circumferentially spaced from the ends of the other mesh sheet and as shown in Fig. 1, the ends 16a and 16b of the mesh sheet 16 are diametrically opposite to the ends 17a and 17b of the mesh sheet 17.

When the end angle irons 16a and 16b of the lower mesh sheet 16 have been drawn sufficiently tight toward each other, they define the vertical side elements of a doorway 21 in their spaced relationship. The door 21 itself comprises a pair of vertically disposed sideboards 27 and 28 bolted respectively to the end faces of the end angle irons 16a and 16b, and into these side boards 27 and 28 are cut a plurality of inwardly and downwardly directed parallel slots 27a and 28a. These parallel slots 27a and 28a are adapted to slidably receive a plurality of closure boards 29 which are inclined downwardly and, therefore, maintain the contents within the crib, but one or more of which may be readily withdrawn when access to the interior of the crib or its contents is desired.

It is to be noted that there has not been provided any additional or separate means for securing the wire mesh sheets 16 and 17 at a multitude of places to the main posts 10 or to the horizontal irons 12 or to the diagonal struts 13. The necessity of such fastening means has been entirely eliminated since the mesh sheets 16 and 17 are so tightly constricted against the outer surfaces of the structural framework that they are self-supporting against vertical movement and are capable of successfully resisting the outwardly directed pressures of the contents of the crib when fully loaded. While the outwardly directed pressures of a full load have a tendency to force the wire mesh out of engagement with the outer surfaces of main posts 10, it has been found that when the mesh sheets 16 and 17 are drawn tightly about the framework, those sheets remain in engagement with the posts 10 at all times. Because the need for such individual mesh securing means has been eliminated, the shipping weight and the time and expense of erection have been reduced to a minimum.

As shown by the broken lines in Figs. 1 and 7, the mesh sheets 16 and 17 when drawn tightly around the structural framework but before the contents are placed in the crib, assume flat planes 55 between the main posts 10, thereby forming a crib that is substantially decagonal in shape with ten substantially flat vertical walls. However, after a crib comprising my invention has been filled to capacity and is, therefore, under full load, the mesh sheets 16 and 17 may assume the slightly rounded out positions illustrated by the solid lines in Figs. 1 and 7. But at no time are these mesh sheets 16 and 17 ever forced out of engagement with the main posts 10. Under normal full load and even under high test loads, the sheets 16 and 17 always remain in engagement with the main posts 10 so as to support those posts against the outward thrust of the contents.

Because the flexible mesh sheets 16 and 17 encompass and tightly engage the outer surfaces of the structural framework under a constricting tension, the mesh sheets 16 and 17 and the main posts 10 and the other bracing members are mutually supporting and are capable of resisting distortion or collapse under extremely heavy

loads. According to the present invention the mesh sheets 16 and 17 are drawn tightly about the posts 10 so as to develop an inwardly directed, constricting pressure thereagainst which pressure is substantially equal to or capable of offsetting the outward thrust of the contents. Thus when the crib is completely filled, the inward and outward pressures against the main posts 10 are in substantial equilibrium. Even if the outward thrust of the contents should become greater than the initial inward thrust of the mesh sheets, no bowing or leaning movement of the posts 10 will occur because of the relatively high tensile strength of the wire mesh sheets 16 and 17, which have been tightly pre-stretched about the framework, and also because of the inherent strength of the braced structural framework itself. Because any bowing or distortion of the posts 10 is successfully prevented, all distortion of the other bracing elements of the structural framework is also successfully prevented.

In many instances, in other types of cribs, where a slight bowing or leaning outwardly of the main posts occurred under load, the inner surfaces of the posts assumed a sloping position instead of being vertical and against which only a side thrust could be exerted by the contents, and hence they were required to support a portion of the vertical load of the contents as well as the sideward thrust. Thus, once a bow or lean in the posts was set up, they were less able than ever to resist further distortion and the pressures thereagainst cumulated as the lean became more pronounced until collapse of the crib finally ensued.

However, because of the structural arrangement of the present invention with the mesh sheets exerting a constricting pressure against the framework of the crib before the posts are under load, any outward lean or bowing of the posts is prevented so that the disastrous cumulative effect is never set up. At the same time with the increased structural strength of the crib, the various elements thereof may be composed of a lighter weight metal stock than would ordinarily be used, which has the effect of reducing manufacturing and shipping costs and increasing the ease of handling during erection. The elimination of the great plurality of individual means of fastening the mesh to the framework also serves to greatly reduce the expense and time required for erection.

Although there has been shown in the drawings and described above, one preferred embodiment of my invention, it will be apparent that

variations and modifications thereof may be made without departing from the underlying principles of the invention. For instance, the general and detailed arrangements of the component parts of the structural framework may be varied in innumerable ways. The number of sides of the crib may be more or less than the ten shown in the preferred embodiment and the number of sections arranged vertically may be increased to three or more with similar results.

I claim:

In a portable storage crib, a knock-down detachable framework adapted to have a sheet of flexible material fastened therearound, said framework comprising a plurality of spaced vertical members, a plurality of straight angle irons disposed transversely between each of said vertical members at both ends of the latter, said angle irons extending angularly from each other and having their horizontal faces extending inwardly to form upper and lower horizontal polygonal edges, strap means connecting the vertical faces of said irons at each end thereof to said vertical members, and a plurality of chordal tie plates disposed in a horizontal plane at the top and bottom of the framework, each of said tie plates having its innermost horizontal face extending across and parallel to an end edge of one of said vertical members and each of said tie plates being secured at its ends to the adjacent horizontal faces of said angle irons in chordal relation with the latter and at points spaced from said vertical members whereby to prevent hinging movement of said angle irons about said vertical members.
